LEWIS B. DOMAN, OF ELBRIDGE, NEW YORK, ASSIGNOR, BY MESNE ASSIGNMENTS, TO
AUTOPIANO COMPANY, A CORPORATION OF NEW YORK.

GUIDE MECHANISM FOR TRAVELING MUSIC-SHEETS.

1,200,175.

Specification of Letters Patent. Patented Oct. 3, 1916.

Application filed March 24, 1908, Serial No. 422,970. Renewed March 5, 1914. Serial No. 822,765.

To all whom it may concern:

Be it known that I, LEWIS B. DOMAN, of Elbridge, in the county of Onondaga, in the State of New York, have invented new and useful Improvements in Guide Mechanism for Traveling Music-Sheets, of which the following, taken in connection with the accompanying drawings, is a full, clear, and exact description.

- 10 This invention relates to certain improvements in guide mechanism for traveling music sheets and refers more particularly to means for automatically maintaining proper registration between the perforations of the music sheet and ducts of the tracker bar. These music sheets are usually made of paper and under varying conditions of humidity they are found to expand and contract more or less thereby varying 15 the width of the music sheet and allowing it to shift laterally relatively to the tracker bar and causing the perforations to similarly shift out of registration with their corresponding vent ducts in the tracker bar.
- 20 This same difficulty may also be caused by irregularities in the trimming of the edges of the music sheet and the primary object of my present invention is to provide means for automatically maintaining exact registration between the perforations in the music sheet and ducts in the tracker bar during 25 the playing of a musical selection. In other words, the broad object of my present invention is to automatically establish a balance of relative position between the music sheet and tracker bar so that abnormal lateral shifting of either of these parts relatively to the other which would tend to bring the perforations of the music sheet 30 out of registration with the ducts of the tracker bar will bring into action means for readjusting or restoring such parts to their normal relative position. These objects may be carried out by automatically shifting the 35 tracker bar endwise relatively to the music sheet or by similarly shifting the music sheet laterally relative to the tracker bar through the medium of a pneumatically balanced movable member and suitable connections between it and the shiftable member together with suitable ducts and connections with the adjusting pneumatic 45 whereby the pneumatic balance of said member may be broken by uncovering one

of the ducts through the shifting of the 55 music sheet or tracker bar thereby causing the action of the movable part of the adjusting pneumatic to readjust such parts to their normal relative position.

In the drawings, Figures 1, 2 and 3 are 60 elevations partly broken away and partly in section of three different forms of devices for carrying out the objects of my invention and Fig. 4 is a detail transverse sectional view through one end of the tracker bar 65 showing one of the pneumatic governor ducts.

In each of the Figs. 1, 2 and 3 is shown a suitable frame —1— in which is mounted a tracker bar —2— and a perforated music 70 sheet —3—, the latter being adapted to be wound and unwound upon and from suitable rollers —4— and —5— which are journaled in suitable bearings in the frame —1— at opposite sides of the tracker bar, 75 said tracker bar being provided with the usual ducts —6— while the music sheet is provided with the usual perforations —7— adapted to register with the ducts —6— as the music sheet is wound from the roller 80 —4— on to the roller —5— during the playing of a musical selection. This tracker bar —2— is also provided with additional vent ducts or ports —8— and —8'— located at opposite ends of a series of ducts —6— 85 and are preferably elongated transversely of the bar and spaced apart from outside to outside a distance substantially equal to the width of the music sheet —3— so that when the perforations —7— are traveling in exact 90 registration with their respective ducts —6—, the edges of the music sheet travel along the outer edges of and therefore just cover the additional ducts —8— to prevent entrance of atmospheric air thereto except 95 when uncovered by the lateral shift or endwise shift of the tracker bar.

The tracker bar —2— is shiftable endwise in suitable guides in the ends of the frame —1— as clearly shown in Figs. 1 and 100 4 while the frame —1— is stationary and the rollers —4— and —5— which carry the music sheet are fixed from endwise movement except as the roller —5— may be removed and replaced in the usual manner 105 when not connected to the music sheet.

The additional vent ducts —8— and —8'— which will hereafter be termed governing

ports are connected respectively by relatively large conduits or passages —9— and —9'— to separate air chambers —10— and —10'— which are located at opposite sides 5 of a movable partition or diaphragm —11—. This diaphragm is provided with a transverse air passage which is connected by a flexible conduit —13— to an exhaust chamber —17— in which a partial vacuum is 10 maintained in suitable air exhausting devices not necessary to herein illustrate or describe as the air exhausting device forms no part of my present invention.

The air passage —12— in the movable 15 diaphragm —11— communicates with the opposite chambers —10— and —10'— through extremely small air passages or bleed holes —14— by which an equal air tension or partial vacuum is normally maintained in the 20 chambers —10— and —10'— and their corresponding ports —8— and —8'— when the latter are covered by the edges of the music sheet —3—.

As previously stated the opposite edges of 25 the music sheet normally cover the ports or governing ducts —8— when the perforations —7— are traveling in registration with their corresponding ducts —6— but if for any reason there is expansion or shrink- 30 age of the paper or irregularity in trimming of the edges thereof, the music sheet should shift laterally sufficient to uncover one of the ports as for instance the port —8—, it would allow atmospheric air to enter the 35 port —8— and thence through the conduit —9— into the exhaust chamber —10— thereby breaking the pneumatic balance of the movable member or diaphragm —11—, and allowing the latter to be drawn or 40 forced toward the opposite side of the pneumatic by the inequality of pressure at opposite sides thereof which causes said movable member to shift the tracker bar —2— in the same direction through the medium of 45 the connecting link —15—. This shifting of the tracker bar again draws the port —8— under cover of the music sheet and restores the registration of the perforations —7— with the ducts —6—.

50 In like manner if the port —8'— is uncovered by the shifting of the music sheet, atmospheric air is at once admitted to the chamber —10'— through the conduit —9'— again breaking the pneumatic balance of the 55 diaphragm —11— causing the latter to be forced or drawn in the opposite direction and thereby restoring the tracker bar to its normal position with the port —8'— under cover of the adjacent edge of the music sheet 60 and the perforations —7— in registration with the ducts —6—, it being understood that as soon as both of the ports —8— and —8'— are brought under cover of the music sheet, the equality of air tension under 65 minus pressure is restored in the chambers

—10— and —10'— causing the diaphragm —11— to assume an intermediate or normal neutral position.

In Fig. 2 is shown the same frame —1—, tracker bar —2—, rollers —4— and —5— and music sheet —3—, but in this instance the rollers with the music sheet thereon are shiftable axially relatively to the tracker bar and for this purpose the ends of both roller spindles are connected by a yoke —20— which in turn is connected by the link —21— to a movable diaphragm —11'— of a double chambered pneumatic. The chambers —10— and —10'— of this pneumatic are separated by the diaphragm —11'—, 70 said chambers being connected by conduits —9— and —9'— to the ducts —8— and —8'— respectively and are also connected by relatively small bleed ducts or passages —14'— to the air exhaust chamber —17— 75 whereby a partial vacuum or minus pressure of equal tension is normally maintained in both chambers. In this modification shown in Fig. 2 the same balance or normal adjustment of the music sheet and tracker bar relatively to each other is maintained 80 by the shifting of the rollers with the music sheet thereon instead of shifting the tracker bar as shown in Fig. 1; otherwise the balancing action is substantially the same as 85 previously described.

In Fig. 3 is shown the frame —1—, tracker bar —2—, rollers —4— and —5— and music sheet —3— but in this instance the frame with the rollers and music sheet mounted therein is shiftable endwise relatively to the tracker bar which is fixed from endwise movement, the means for shifting the frame and parts mounted therein being substantially the same as shown in Fig. 1 105 except that the movable diaphragm —11— is connected to the frame through the medium of a link —15'— and lever —16—.

It will be seen from the foregoing description that in Fig. 1, the tracker bar is shiftable endwise relatively to the music sheet while in Figs. 2 and 3 the music sheet is shiftable relatively to the tracker bar but in each modification, the means for effecting the shifting movement or adjustment of the 110 tracker bar and music sheet relatively to each other is substantially the same both being dependent upon a pneumatically balanced movable member connected in the manner described.

It will be observed from the foregoing description that the chambers of the shifting pneumatics by which normal relation between the music sheet and governing ports is maintained, communicate through 115 relatively small air passages or bleed holes with the exhaust chamber —17— and also communicate through relatively large air passages or ducts with the governing ports. It therefore follows that the air in both 120

chambers is normally under uniform tension and that the movable diaphragm between said chambers is normally balanced as long as normal relation is maintained between the music sheet and its governing ports, but should one of the ports be uncovered or opened to the atmosphere, it is clearly evident that the sudden inrush of atmospheric air to the corresponding chamber would cause said diaphragm to move toward the side of lowest pressure. This movement, however, would be slow by reason of the slow escape of air from the low pressure chamber through the relatively small bleed hole and it is this slowness of action which is desired because if the tracker bar or music sheet supports were shifted suddenly or at the instant either governing port was uncovered the slightest degree, such tracker bar or supports would be carried too far in one direction or the other and there would be a tendency to keep such parts in continued vibration. Another reason why this slowness of action is desired is to prevent the shifting of the tracker bar or music sheets in case of a slight mutilation of the edge of the sheet which might for an instant uncover one of the ports and thereby throw the parts out of adjustment, whereas if the shifting action is slow, the mutilated portion would have passed the part before the normal relation was disturbed.

What I claim is:

35. 1. The combination of a tracker bar having a series of music apertures, means for drawing a perforated note sheet forward over the tracker bar, two pneumatic control openings appurtenant to the tracker bar and arranged for coöperation with the note sheet, a double-acting pneumatic motor connected to adjust the lateral relation between the note sheet and tracker bar, said pneumatic motor having two chambers, a connection between one chamber and one control opening, and a connection between the other chamber and the other control opening arranged so that when the note sheet shifts to one side or the other, air will pass through one control opening and one connection into one of the chambers of the pneumatic, which will expand to restore the normal lateral relation between the tracker bar and note sheet.
55. 2. The combination of a tracker bar having a series of music apertures, means for drawing a perforated note sheet forward over the tracker bar, two pneumatic control openings appurtenant to the tracker bar and arranged for coöperation with the note sheet, a double-acting pneumatic motor connected to adjust the lateral relation between the note sheet and tracker bar, said pneumatic motor having two chambers, a connection from the exhaust having a restricted opening into each chamber, whereby the motor will be balanced when there are equal air tensions in the two chambers, a connection between one chamber and one control opening, and a connection between the other chamber and the other control opening arranged so that when the note sheet shifts to one side or the other, air will pass through one control opening and one connection into one of the chambers of the pneumatic, which will expand to restore the normal lateral relation between the tracker bar and note sheet.

3. Guide mechanism for traveling music sheets comprising a tracker, a double motor having a movable member normally balanced at equal air tensions on opposite sides thereof, a traveling sheet, air ports normally in the same condition when the traveling sheet is in normal position communicating with opposite sides of the movable member and adapted to have their condition changed by the shifting of the sheet from its normal line of travel, whereby atmospheric air admitted through the changed condition of a port to the corresponding side of the member causes the operation of the latter, and means operated by the movement of said member for restoring the normal relation between the sheet and tracker.

4. Guide mechanism for traveling music sheets comprising a tracker, a movable member normally balanced at equal air tensions on opposite sides thereof, a traveling sheet, air ports normally closed when the traveling sheet is in normal position and communicating with opposite sides of the movable member, one opening adapted to be opened when the sheet shifts in one direction from normal and the other opening to be opened when the sheet shifts in the other direction from normal, whereby atmospheric air admitted through an open port to the corresponding side of the member causes the operation of the latter, and means operated by the movement of said member for restoring said normal relation between the sheet and tracker.

5. Guide mechanism for traveling music sheets comprising a movable member normally balanced under equal air tension at opposite sides thereof, the traveling sheet air-ports normally closed by opposite edges of the traveling sheet and communicating with opposite sides of the movable member and adapted to be opened by the shifting of the sheet from its normal line of travel whereby atmospheric air is admitted through the opened port to the corresponding side of said member to cause the operation of the latter, and means operated by the movement of said member for restoring normal relation between the sheet and ports.

6. Guide mechanism for traveling music sheets comprising an exhaust-chamber, air-

- chambers communicating with said exhaust-chamber through relatively small passages, the traveling sheet air-ports normally covered by the edges of the music sheet and 5 communicating with the air-chambers through relatively larger passages, a movable member between and normally balanced under the equal air-tension in said air-chambers and adapted to be operated by the in- 10 rush of atmospheric air to one of the air-chambers in case the corresponding port is uncovered by the music sheet, and means actuated by such operation for bringing the sheet and ports into normal relation.
- 15 7. Guide mechanism for traveling music sheets comprising in combination with the traveling sheet relatively large air passages having ports normally closed to the atmosphere by the music-sheet and adapted to be 20 opened by abnormal positions of the port covering portions of the sheet, relatively smaller air-passages in which a partial vacuum of equal tension is maintained, said smaller passages communicating with their 25 respective larger passages, and means in- cluding pneumatic chambers and a movable member brought into action by the opening of either of the ports for restoring normal relation between said ports and music sheet.
8. In combination with a traveling music sheet and tracker-bar of a self-playing musical instrument, an exhaust chamber, pneumatics communicating through bleed ducts with the exhaust chamber, air-ports on the tracker-bar normally closed by portions of the music sheet and adapted to be opened to the atmosphere by abnormal relation between said sheet and ports, said ports communicating through relatively larger ducts with said pneumatics for operating the latter when either port is opened, and means for transmitting motion from the pneumatics to the tracker-bar to restore normal relation between the sheet and ports. 35
- In witness whereof I have hereunto set my hand this 21st day of March, 1908.
- LEWIS B. DOMAN.
